UNITED STATES PATENT OFFICE.

ALFRED COTTON, OF ST. LOUIS, MISSOURI, ASSIGNOR TO HEINE BOILER COMPANY, OF ST. LOUIS, MISSOURI, A CORPORATION OF MISSOURI.

SUPERHEATER BOILER.

Application filed April 12, 1920. Serial No. 373,248.

To all whom it may concern:

Be it known that I, ALFRED COTTON, a citizen of the United States, residing at St. Louis, Missouri, have invented a certain new and useful Improvement in Superheater Boilers, of which the following is a full, clear, and exact description, such as will enable others skilled in the art to which it appertains to make and use the same.

10 This invention relates to water tube boilers of the Stirling type.

The main object of the invention is to provide a superheater boiler that is superior to the usual Stirling boiler, in that it produces drier steam; it insures more complete combustion of the fuel and eliminates smoke; it has a greater steaming capacity and it is less expensive to manufacture than many kinds of Stirling boilers now in use.

20 Another object is to provide a superheater boiler of the Stirling type which is so designed that greater latitude is allowed in the arrangement of the superheater.

Briefly described, my present invention 25 consists of a water tube boiler comprising four banks of water tubes and drums arranged so that the water will circulate upwardly from the mud drum or feed water chamber through the first and second banks 30 of tubes and return to the mud drum through the third bank of tubes or mainly through the third bank and partly through the fourth bank of tubes through which the feed water is supplied to the mud drum, and 35 a superheater arranged in such a manner that it will be heated by the gases traveling through the boiler. It embodies all of the good features and characteristics of the four bank boiler described in my pending application for patent Serial No. 366,286, filed March 16, 1920, with the added advantage of a 40 superheater; and it is distinguished from the usual Stirling boiler principally by reason of the fact that two separate and distinct 45 banks of tubes lead upwardly from the feed water chamber or mud drum to separate and distinct elevated drums or chambers so as to permit the upwardly circulating water to enter separate and distinct elevated 50 chambers, instead of a single steam-and-water drum, as in the usual Stirling boiler. By constructing the boiler in this manner I eliminate the possibility of water becoming entrained with the steam and carried into the space from which the supply of steam

is taken, I eliminate the possibility of the water level in the rear elevated drum dropping sufficiently to expose the upper ends of the feed water tubes and cause them to become dry and overheated to such a degree 60 that their expanded joints leak, and I eliminate the possibility of the furnace gases becoming chilled below their ignition point before combustion is completed, thus resulting in loss of efficiency, and the production 65 of heavy smoke, all as explained clearly in my pending application for patent previously referred to.

Figure 1 of the drawings is a vertical sectional view of a superheater boiler constructed in accordance with my invention.

Figure 2 is a similar view, showing the superheater arranged in a slightly different manner; and

Figure 3 is a vertical sectional view of 75 a superheater boiler embodying my invention and provided with a submerged drum that communicates with the upper ends of the tubes of the radiant heat bank.

Referring to Figure 1 of the drawings, 80 which illustrates one form of my invention, A designates a set of water tubes which may be called the radiant heat bank of the boiler, B designates another set of water tubes which may be called the convected 85 heat bank, C designates another set of water tubes which may be called the downcomer bank and D designates another set of water tubes which may be called the economizer bank. The radiant heat bank A and 90 the convected heat bank B lead upwardly from the mud drum or feed water chamber 1 to a front steam-and-water drum 2 and to a middle steam-and-water drum 3, respectively. The downcomer bank C leads 95 downwardly from the middle drum 3 to the mud drum 1 and the economizer bank D through which the feed water is supplied to the mud drum leads downwardly to the mud drum from the rear steam-and-water 100 drum 4.

The front bank or radiant heat bank A consists of only a few rows of tubes that are exposed to the radiant heat of the fire and of the combustion chamber α . Preferably this radiant heat bank is composed of two rows of tubes which are the only tubes discharging into the front steam-and-water drum 2, but if desired, the radiant heat bank A may consist of three rows of tubes. In 110

all cases, however, the cross-sectional area of the tubes of the radiant heat bank will be less than the cross-sectional area of the tubes of the convected heat bank B. The 5 front drum 2 is connected to the middle drum 3 by means of water circulators 5 and steam circulators 6, and said middle drum is connected with the rear drum 4 preferably by means of water circulators 7 and 10 steam circulators 8, the outlet 9 for the steam produced in the boiler preferably leading from the upper side of the rear drum 4.

The baffles of the boiler can be arranged in various ways without departing from the 15 spirit of my invention, so long as the boiler is equipped with four banks of tubes combined with a mud drum or feed water chamber and elevated drums or chambers in such a manner that the water that circulates upwardly from the mud drum will enter separate and distinct drums or chambers that communicate with the first and second tube banks of the boiler, and a superheater arranged in such a manner that it will be 20 heated by some of the gases flowing through the boiler. In the form of my invention illustrated in Figure 1 a front baffle 10 extends upwardly from the mud drum 1 at the rear side of the radiant heat bank A to a point in proximity to the front steam-and-water drum 2, a second baffle 11 is arranged at the front side of the down-comer bank C and extends downwardly from the middle steam-and-water drum 3 to a point in proximity 25 to the mud drum 1, and a third baffle 12 is arranged between the down-comer bank C and the economizer bank D, so as to cause the gases to flow upwardly between the tubes of the down-comer bank C, then downwardly between the tubes of the economizer 30 bank to an outlet 13.

Since the flow of steam and water into the front steam-and-water drum 2 is very much less in my boiler than in the usual 45 Stirling boiler, the water in the front drum of the boiler is much calmer and a much better separation of the steam and water is obtained. Furthermore, there is little liability of the water level in the front drum 2 rising 50 abnormally or the water becoming entrained with the steam and carried over with the steam into the steam space of the middle drum 3, thus insuring the production of drier steam, even when the boiler is driven 55 at rates much higher than is considered reasonable practice with the usual Stirling boiler.

Since the water flowing up the convected heat bank B flows directly across the middle 60 steam-and-water drum 3, without having to encounter the resistance to flow of any water circulators, as in the regular Stirling boiler, the flow to the down-comer bank C is free. The water circulators 7 leading from the 65 middle drum 3 to the rear drum 4 raise the

temperature of the feed water sufficiently to prevent corrosion on the tubes of the economizer bank caused by condensation of water vapor in the gases flowing through the last pass of the boiler. The flow of 70 the water through the circulators 7 also tends to prevent the level of the water in the rear drum 4 from dropping abnormally, but in view of the fact that my boiler is so constructed that there is practically no restriction to the circulation of the water upwardly from the mud drum, the lowering of 75 the water level in the rear drum 4 is unobjectionable, even at high driving rates.

In a boiler of the construction above described 80 three spaces are available for a superheater, and the choice of position is dictated by the amount of superheat desired, namely, the temperature of the superheated steam. The gases flowing in the 85 space between the first and second banks are too hot for the amount of superheat generally required. Although the superheat may be regulated by controlling the amount of gases flowing over the superheater, as in 90 the form of my invention illustrated in Figure 2 and hereinafter described, it is 95 advisable to use gases hotter than necessary, as this causes the superheater elements to deteriorate rapidly. The temperature of the 95 gases flowing in the space between the third and fourth banks of tubes is so much reduced that only a small degree of superheat would result, unless an impractically large superheater were used. In general practice 100 I prefer to arrange a superheater E between the second and third banks B and C, on account of the fact that the gases flowing through this space are of such a temperature that the amount of superheat required in 105 usual practice is easily attained with a compact superheater that can be used for a long period without the elements of same deteriorating. In Figure 1 of the drawings I have shown my improved boiler equipped 110 with a superheater E arranged so that the gases will flow downwardly over same and over the tubes of the second bank in one common pass. The amount of gases flowing over each course can be accurately controlled, but I prefer to arrange one or more horizontally-disposed baffle shelves 10^a on the rear side of the front baffle 10 and a horizontally-disposed baffle shelf 11^a at a 115 point between the superheater E and the convected heat bank B, so as to cause the gases that flow over the upper edge of the front baffle 10 to flow downwardly over the convected heat bank B and also over the superheater E and then flow upwardly 120 among the tubes of the down-comer bank C, as indicated by arrows in Figure 1, said gases escaping downwardly through the last pass to the outlet 13. It is not essential, 125 however, that the superheater and the baf- 130

bles be arranged in the manner shown in Figure 1, for if desired, the boiler can be so constructed that the gases flowing over the superheater will be in common with the 5 gases flowing along the third bank.

In Figure 2 of the drawings I have shown the superheater E arranged between a baffle 11 located in the front portion of the down-comer bank C, and a baffle 14 arranged at the rear side of the convected heat bank B, the upper end of said baffle 14 being spaced away from the middle drum 3, and the lower end of said baffle being spaced away from the mud drum 1, so as to cause 10 part of the gases to flow downwardly over the convected heat bank B and the remainder of the gases to enter the upper end of the superheater chamber and flow downwardly through same, as indicated by the 15 arrows in Figure 2. A damper 15 is preferably provided so as to enable the amount of superheat to be accurately controlled.

The fact that the draft pressure at the outlet or lower end of the superheater chamber 20 is less than the draft pressure at the inlet to said chamber insures an ample flow of 25 hot gases through the superheater chamber when the damper 15 is open. The gases which have passed over the superheater E 30 are still at a sufficiently high temperature to give up a considerable quantity of heat to the cooler heating surface of the boiler, and consequently, the gases which escape 35 from the superheater chamber can be returned to the main body of gases early enough to transmit heat to the third and fourth tube banks of the boiler.

The spaces between the various banks of tubes of my improved boiler are just as accessible as in the usual Stirling boiler, and 40 as there is one additional space, greater latitude is allowed in the arrangement of the superheater. The space of the boiler in which it is desired to locate the superheater 45 can be increased sufficiently to accommodate the superheater and to provide sufficient room for access to the superheater, as well as to the boiler tubes, by slightly reducing the size of the other two spaces between the 50 banks of tubes.

In Figure 3 of the drawings I have illustrated still another form of my invention, wherein the radiant heat bank A leads upwardly from the mud drum 1 to a submerged water drum F. In all other respects the boiler shown in Figure 3 is substantially the same as the boiler shown in Figure 1, except that steam circulators are not arranged between the submerged water 55 drum and the steam-and-water drum 3.

Having thus described my invention, what I claim as new and desire to secure by Letters Patent is:

1. A water tube boiler, comprising at 60 least two elevated transverse steam-and-

water drums, water circulators connecting said drums together, a transverse mud drum, a radiant heat bank of upflow tubes leading upwardly from said mud drum to one of said elevated drums and constituting 70 the sole source of water supply to said elevated drum, a separate and distinct convected heat bank of upflow tubes spaced away from said radiant heat bank and connected to the other elevated drum for causing 75 the remainder of the water rising from said mud drum to circulate upwardly to said other elevated drum, a baffle arranged between said radiant heat bank and said convected heat bank, a co-operating baffle 80 for causing the fire gases to flow downwardly among the tubes of the convected heat bank, downcomer tubes leading from one of said elevated drums directly to said mud drum, and a superheater arranged so 85 that it will be heated by gases flowing through the boiler.

2. A water tube boiler, comprising three elevated transverse steam-and-water drums, water circulators connecting the front drum 90 with the middle drum, a transverse mud drum, a radiant heat bank of upflow tubes leading upwardly from the mud drum to the front steam-and-water drum and constituting the sole source of water supply to 95 said front drum, a separate and distinct convected heat bank of upflow tubes leading upwardly from the mud drum to the middle drum for causing the remainder of the water supplied to said mud drum to circulate 100 upwardly to said middle drum, a baffle arranged between the radiant heat bank and the convected heat bank, downcomer tubes leading from the middle drum to the mud drum, an economizer bank of 105 tubes leading from the rear steam-and-water drum to the mud drum, and a superheater arranged in a space between two adjacent tube banks of the boiler.

3. A water tube boiler, comprising three 110 elevated transverse steam-and-water drums, steam-and-water circulators connecting the front drum with the middle drum and the middle drum with the rear drum, a transverse mud drum, a radiant heat bank of upflow tubes leading upwardly from the mud drum to the front steam-and-water drum and constituting the sole source of water supply to said front drum, a separate and distinct convected heat bank of upflow tubes 115 spaced away from the radiant heat bank for conducting the remainder of the water supplied to the mud drum upwardly to the middle steam-and-water drum, a baffle arranged between the radiant heat bank and the convected heat bank and a co-operating baffle for causing the fire gases to flow 120 downwardly among the tubes of the convected heat bank, downcomer tubes leading from the middle steam-and-water drum to 125 the mud drum.

4. A water tube boiler, comprising at least two elevated transverse steam-and-

the mud drum, an economizer bank of tubes leading from the rear steam-and-water drum to the mud drum, and a superheater arranged in the space between the convected heat bank and the downcomer tubes.

4. A water tube boiler, comprising at least two elevated transverse steam-and-water drums, a transverse mud drum, a radiant heat first bank of upflow tubes leading from the mud drum to the front steam-and-water drum and arranged at the rear of the combustion chamber outside of the main path of flow of the gases, water circulators connecting said elevated steam-and-

water drums together, a convected heat second bank of upflow tubes leading from the mud drum to the second steam-and-water drum for causing the remainder of the water rising from the mud drum to pass directly into said second steam-and-water drum, a baffle between the first and second banks, downcomer tubes leading from the second steam-and-water drum directly into said mud drum, and a superheater arranged in the space between the convected heat bank and the downcomer tubes.

ALFRED COTTON.
